UNITED STATES PATENT OFFICE.

DAVID S. KENNEDY, OF BROOKLYN, NEW YORK, ASSIGNEE TO MERGENTHALER LINOTYPE COMPANY, A CORPORATION OF NEW YORK.

TYPOGRAPHICAL MACHINE.

1,122,604.

Specification of Letters Patent. Patented Dec. 29, 1914.

Application filed June 21, 1912. Serial No. 764,940.

To all whom it may concern:

Be it known that I, DAVID S. KENNEDY, a citizen of the United States, and a resident of Brooklyn, county of Kings, and 5 State of New York, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in 10 the order in which their characters are to appear in print and then assembled in line, the composed line transferred to the face of a mold, the mold filled with molten metal to form a slug or linotype against the matrices which produce the type characters thereon, and the matrices thereafter elevated and returned through a distributing mechanism to the magazine from which they started. 15 More particularly, it has reference to the parts which receive the matrices from the distributing mechanism. In machines of this kind, the matrices pass from the distributing mechanism into and through a channeled entrance, which in turn delivers them to the channeled magazine, and to this end the magazine and the entrance are caused to register in such manner that their corresponding channels are practically continuous. The matrices are of varying size, 20 depending both on the characters represented thereby and on the different styles or fonts in use, ranging for instance from a very thin one containing a punctuation mark to a very thick one representing a "head-letter". As the several fonts which are successively employed may thus contain matrices of widely different size and thicknesses, it has been customary to vary the 25 relative width of the entrance channels to correspond, and this result has been generally secured by bending the lower ends of certain of the channel partitions, when the font is changed, the bending being sometimes performed manually and some times automatically.

It is one of the purposes of my present invention to obviate this necessity and to employ channels of permanent width, which 30 channels are provided with guiding means

adapted to engage the ears of all matrices, whether thick or thin, and consequently to guide them into correct relation to the magazine.

In the accompanying drawing I have shown my invention in preferred form and by way of example, and as applied to a linotype machine, but obviously many variations and alterations may be made therein, and further it may be adapted to other forms of typographical machines, such as typesetters, typecasters, and the like; (in other words, to handle type, etc.), without departure from its spirit.

Generally speaking, I desire it to be distinctly understood that I do not limit myself to any specific form or embodiment except in so far as such limitations are specified in the claims.

Similar subject matter is disclosed in the application for Letters Patent of Millard Butts, Serial No. 697,045, filed May 18, 1912, wherein are also shown guiding means to engage the ears of the matrices, but in the specific form there illustrated, they are all formed upon the entrance partitions. My improved devices are of the same general character, but embody guiding means formed upon one of the side plates of the magazine entrance, and preferably upon that part thereof which is movably mounted to give access to the interior, this arrangement being especially desirable, as it permits the ready disengagement of the parts and the easy manipulation of the contained matrices. Further, in the event of the lodgment of a matrix partly in the magazine and partly in the entrance, and an attempt to shift the entrance laterally away from the magazine, this construction allows the pivoted plate to yield, which capability is not present, if the guiding means are entirely located upon the partitions, as in the said Butts application.

Referring to the drawing: Figure 1 is a transverse vertical section through the magazine entrances, the upper end of the magazines, the distributing devices, etc.; and Fig. 2 is a detail rear view of the front plates of a magazine and its entrance.

The matrices X are moved by the distributor screws S along the rails or bars R, from which they are released at the proper points and pass into the magazine entrance E and therethrough into the magazine M.

105

110

The matrices are of the ordinary form and are provided with the projecting ears X^1 , which engage in the side grooves M^1 of the magazine. As in the said Butts application, 5 the bodies of the matrices may vary in size from very thin to very thick, although their ears are all adapted to engage and travel in the grooves M^1 without regard to their body dimensions. The magazine entrance 10 E is divided into channels by the partitions N , and is provided with inner and outer plates B and A , the outer plate A having the pivotally mounted member or gate P , all in the ordinary manner.

15 In order that the matrices may be properly guided into the magazine, the entrance channels near their lower ends are provided with means to engage the matrix ears laterally, in a manner substantially similar to 20 that disclosed in the said Butts application, except that therein these guiding means are specifically illustrated as formed upon the entrance partitions. In the present instance, I locate the guides P^1 for the front 25 ears X^1 of the matrices upon the movable gate P , and the guides N^1 for the rear ears upon the partitions N .

As in the Butts construction, the matrices X in passing through the entrance E are 30 guided by the lateral contact of these guides P^1 and N^1 with their ears X^1 , so that the ears are directed accurately and with certainty into the magazine grooves M^1 , M^1 , of the magazine, and this quite irrespective of 35 the body thicknesses of the matrices.

The particular advantage involved in my improved construction are: first, that the opening of the gate P displaces the connected guides P^1 , so as to give ready access 40 to the interior and facilitate the manipulation of the contained matrices; and, second, that if an attempt be made to shift the magazine entrance as a whole with reference to the magazine, at a time when a matrix or matrices are lodged in engagement 45 with both of them, the gate P will yield and thus prevent bending or breakage. These advantages and points of convenience are not present, when the matrix guides are 50 formed at both sides upon the channel partitions, as in such construction the fixed front guides are not only an obstacle to the easy manipulation of the contained matrices, but also may prevent the free lateral shifting 55 of the entrance with reference to the magazine.

Having thus described my invention, its construction and mode of operation, what I claim and desire to secure by Letters Patent of the United States is as follows:

60

1. In a typographical machine, the combination of a channeled magazine, and a separate matrix delivery entrance therefor having a series of channels, one for each channel of the magazine, the said entrance 65 being provided with a movable part formed with guiding portions projecting partly across its channels to engage the matrices and insure their proper entrance into the magazine.

70

2. A channeled matrix delivery entrance comprising top and bottom walls, one of said walls being provided with a part formed with matrix guiding surfaces projecting partly across the channels, and the 75 said part being movable relatively to the remaining part of the wall.

80

3. In a typographical machine, the combination of a channeled magazine, and a matrix delivery entrance therefor comprising inner and outer plates and a series of intermediate partitions forming between them channels, one for each channel of the magazine, one of said plates being provided with guiding surfaces projecting partly 85 across the channels of the entrance to cooperate with the matrices in their passage to the magazine.

85

4. In a typographical machine, a channeled magazine entrance comprising inner 90 and outer plates and a series of partitions therebetween, and having supplemental matrix guiding surfaces projecting partly across the channels and located in part upon one of the plates, and in part upon 95 the partitions.

100

5. In a typographical machine comprising matrices formed with projecting ears, a channeled magazine entrance comprising inner and outer plates and a series of intermediate partitions and having guiding surfaces located upon one of said plates and projecting partly across the channels to engage only the ears of the matrices.

In testimony whereof I hereunto set my hand this 19th day of June, 1912, in the presence of two attesting witnesses.

DAVID S. KENNEDY.
